TYPEWRITER CASE

Paul B. Witmer, Lancaster, Pa.

Application September 20, 1937, Serial No. 164,791

1 Claim. (Cl. 45—68.2)

My invention relates to typewriter cases and more particularly to cases in which portable typewriters are contained.

One of the principal objects of my invention is to provide a typewriter case fashioned with a tray for holding stationery and the like, together with means for maintaining the tray in closed position when the cover of the case is closed.

Another object of my invention is to provide a case of the above described character equipped with means for preventing the accidental opening of the tray when the cover has been removed or is in open position.

Other objects and advantages will be apparent from the following description, appended claim and annexed drawing.

Referring to the drawing wherein like reference characters designate like parts throughout the several views:

Fig. 1 is a side elevation of my invention.

Fig. 2 is a sectional view taken on a line 2—2 of Figure 1.

Fig. 3 is a sectional view taken on a line 3—3 of Figure 2.

Fig. 4 is a sectional view taken on a line 4—4 of Figure 1.

Fig. 5 is a detail sectional view taken on a line 5—5 of Figure 4.

Fig. 6 is a detail sectional view taken on a line 6—6 of Figure 3.

In practicing my invention, in the preferred embodiment illustrated in the drawing, I employ a typewriter case 5 having a cover 6 equipped with a carrying handle 7 and a base section 8 connected to said cover at one end by separable hinges 9. The case is of a general construction adapted for use in housing and transporting portable typewriting machines and the like.

The base section 8 is formed with spaced walls 10, 11, 12 and 13, respectively, forming a tray chamber 14 open at the front end of said section.

The bottom wall 11 has secured thereto a track comprising spaced parallel headed rails 15 extending from the rear to the front of said chamber. Mounted for sliding engagement on the rails 15 is a tray 16 having a bottom formed with shouldered slots embracing the heads of the rails 15 to prevent accidental displacement of the tray from the rails. Rubber bumpers 17 are secured to the outer face of the rear wall of the tray for abutting engagement with the wall 13 to cushion the closing movement of the tray and to tension the front end of the tray against the inner face

of a depending section 18 of the cover 6 herein-after described.

The interior of the tray adjacent the rear wall thereof is provided with a transversely extending shaft 19 having ends slidable within slots 20 formed in a spring housing 21 secured to the bottom of the tray adjacent the crotch formed by the rear and side walls of the tray. The ends of the shaft are fashioned with spring seats 22 for engagement with coil springs 23 interposed between the top wall of the housing and said seats.

A rectangular plate 24 is pivoted at one end about the shaft 19 and is maintained in tensioned relationship thereto by means of a pair 18 of coil springs 25, each of said springs having one end secured to the shaft 19 and the other end engaging the plate 24 whereby the plate 24 is normally urged downwardly towards the bottom of the tray.

The tray is adapted to receive stationery and the like, the plate 24 functioning to engage and hold the stationery between the bottom of the tray and said plate due to the action of the springs 25. To compensate for variation in thickness of the stationery secured within the tray at various times in order that the plate 24 may engage the stationery in a parallel plane with the upper face of the stationery, the ends of the shaft 19 are adjustable within the housing 21 due to the yieldability of the springs 23.

The outer ends of the tray are equipped with means for preventing accidental actuation of the tray when the cover is removed or in opened position in relation to the base section. Said means comprises spring pressed plungers 26 secured to the ends of leaf springs 27 connected to the inner faces of the side walls of the tray adjacent the front end. The plungers operate through suitable openings 28 formed in the sides of the tray 40 and the outer ends of the plungers are adapted to engage plates 29 secured to the inner faces of the side walls 12 of the base section adjacent the front end thereof. The tension of the springs 27 is such as to prevent the plungers 26 from being camed to ride over the plates 29 upon accidental sliding movement of the tray and to permit the same to be camed to effect an opening of the tray when desired. The bottom of the tray adjacent the front end thereof is formed with a finger aperture 30 whereby the tray may be readily pulled out from within the chamber 14 to an opened or accessible position.

The bottom wall 11 has secured thereto intermediate of the side walls 12 a staple member 31

for securing thereto a hasp 32 carried by the depending section 18 of the case, a suitable form of locking means being employed to lock the same thereto. The top wall of the base section is formed with a plurality of recesses 33 for receiving the rubber mountings of a portable typewriter adapted to be supported on the base section and enclosed when not in use by the cover 8.

- 5 In use, it will be apparent from the foregoing, when the cover is raised to open position or detached from the base section 8 to expose the typewriter for use, the depending section 18 secured to the cover will be removed from in front of the opened end of the chamber 14 thereby permitting the tray to be withdrawn therefrom to an opened position. Furthermore, when the cover is moved to a closed position, the tray being in the closed position illustrated in Figure 3, the depending section 18 of the cover will effectively 10 close the open end of the chamber 14 and maintain the tray in a closed position therein and permit the stationery carried within the tray to be protected from becoming lost or disarranged.
- 15 20 It will also be noted that when the case is locked

to prevent unauthorized persons from using or having access to the typewriter the stationery will also be locked within the chamber against access by said persons.

What I claim is:

In a carrying case for typewriters of the class wherein the body section thereof is fashioned with spaced walls forming a tray chamber having an open front end and including tracks secured to the bottom wall therein and the cover attached to the body section is formed with a section overlying the front of the chamber; the combination of a tray having an open front and formed with a bottom provided with guideways embracing the tracks whereby the tray is operable over the latter into and out of the chamber, and latching devices carried by the tray adjacent the front end thereof for engagement with a pair of the walls of the body section to maintain the tray in retracted position within the body; said cover section when overlying the front of said chamber coacting with the body section to enclose the tray therein.

PAUL B. WITMER.
